UNITED STATES PATENT OFFICE.

ORED OLSSON, OF ORD, NEBRASKA.

WINDMILL.

1,360,013.

Specification of Letters Patent. Patented Nov. 23, 1920.

Application filed February 17, 1920. Serial No. 359,244.

To all whom it may concern:

Be it known that I, ORED OLSSON, a citizen of the United States, and a resident of Ord, in the county of Valley and State of Nebraska, have invented a new and Improved Windmill, of which the following is a full, clear, and exact description.

This invention relates to improvements in windmills, and more particularly to improvements upon the windmill disclosed in Patent No. 626559, granted to me June 6, 1899, an object of the invention being to provide improved means for constructing and connecting the blades or vanes with the operating mechanism.

A further object is to provide an improved construction and mounting for the governor.

A further object is to provide improved means for preventing the windmill from being forced out of operation by a sudden blast of air.

A further object is to provide a windmill which embodies in its construction various novel details which coöperate in the provision of a wind wheel which will most efficiently perform the functions for which it is intended.

With these and other objects in view the invention consists in certain novel features of construction, and combinations and arrangements of parts as will be more fully hereinafter described and pointed out in the claims.

In the accompanying drawings—

Figure 1 is a view in side elevation with certain of the blades or vanes and operating parts removed for purposes of clearness;

Fig. 2 is a view in elevation at right angles to Fig. 1;

Fig. 3 is an enlarged view in longitudinal section through one of the blades or vanes, the section being taken on the line 3—3 of Fig. 1;

Figs. 4, 5 and 6 are transverse sectional views of a blade or vane, said sections being indicated by the lines 4—4, 5—5, and 6—6 respectively of Fig. 1;

Fig. 7 is a fragmentary view in elevation illustrating the normal position of the device for preventing the wind wheel from being forced out of operation by a blast of air, an abnormal position of its controlling mechanism being illustrated at the left of Fig. 1;

Fig. 8 is a view similar to Fig. 7 showing another position of parts; and

Fig. 9 is a fragmentary perspective view illustrating the manner of connecting the braces and stays.

My improved windmill is designed in such a manner that it may be constructed entirely of metal, is entirely automatic in its action and is so mounted as to obviate the necessity for a regulating vane, the mill being so mounted relative to its pivot that it will at all times swing to such a point that it will face the wind. The mill is also provided with a governor so connected with the vanes that they will be turned at an angle to the wind corresponding with its speed and extremely high winds will turn the flat blades or vanes so that they present much less surface to the wind.

The mill is supported upon a cast metal frame A, the latter having a rotary bearing or pivot 1 mounted upon the upper end of standards 2 and adapted to turn freely in accordance with the direction of the wind. A horizontal bearing sleeve 3 is provided integral the frame A and provides mounting for a horizontal shaft 4. A drive pinion 5 is fixed to one end of the shaft 4 and meshes with a gear wheel 6, the latter mounted upon a shaft 7 supported in a bearing 8 above the sleeve 3. A crank pin 9 is provided on the gear wheel 6 and is connected by a link 10 with the plunger rod 11, the latter projecting through the frame A and extending to any desired point.

A hub 12 is fixed on the shaft 4 and is provided with a series of radial spokes 13, the latter supporting at their outer ends blades or vanes 14 which are preferably of sheet metal and the outer ends of said spokes are supported and strengthened by means of guys 15 and 17 connected at opposite sides of the spokes, the guys 15 extending to and secured to a disk 16 fixed on the bearing sleeve 3. The guys 17 extend in the opposite direction and are secured to a disk 18 which is located on the shaft 4 and clamped between nuts 19 on the screw threaded end 20 of said shaft.

The blades or vanes 14 are connected at or near their edges by stays 24 which compel them to turn together so that their angular disposition will always be the same. A governor B is provided on the shaft 4 and is

made with weighted governor arms 22 pivotally supported on brackets 23 and connected to certain of the blades by stays 45 to automatically control the angular disposition of the blades. The governor B comprises two pairs of pivoted links 25 which are connected to the arms 22 at their intermediate pivotal connection. These arms 25 at one end are connected to a sliding sleeve 10 26 mounted on the shaft 4 and engaged by a coiled spring 27 on said shaft. The other ends of the arms 25 are connected to a collar 28 mounted on a sliding sleeve 29, said sleeve adapted to slide on the outer face of 15 the bearing sleeve 3.

A link 30 is pivotally connected to the sleeve 29 and projects through the disk 16 and is guided in its longitudinal movement by parallel webs 31 on one side of the bearing sleeve 3. A rod 32 connects this link 30 with a bell crank lever 33 mounted on an upwardly projecting arm 34 of frame A. An arm 35 is pivotally connected to one end of the bell crank lever 33 as shown at 36, and a 20 coiled spring 37 connects the upper end of the arm 35 with the other member of the bell crank lever 33 normally holding said lever against a shoulder 38 on the lever. A lug 39 projects from the arm 35 adjacent its pivot 36 and an operating rod 40 is connected to the lug 39. The arm 35 may be made with an adjusting bolt 41 at its lower end to vary the length of the arm for a 25 purpose which will hereinafter appear.

Fig. 7 illustrates the normal position of the arm 35. Fig. 8 shows the position of the arm when a sudden gust of wind strikes the blades or vanes and operates the governor which would tend to straighten the 30 blades and prevent any turning movement of the wind wheel unless such movement were limited, and it will be noted that in Fig. 8, the lower end of the arm 35 engages the frame A and limits the further movement of the parts.

When it is desired to throw the wind wheel entirely out of operation, a pull is had on the rod 40, which first swings the arm 35 to the position shown in Fig. 1 with 35 the lower end of said arm to one side of the frame A, and hence, a continued pull on the rod will move the governor links so as to throw the blades or vanes entirely out of operation. When the rod 40 is released, the parts will return to normal position, the 40 spring 37 drawing the arm 35 against the shoulder 38, as illustrated in Fig. 7.

Pairs of double or parallel guy rods 41 are provided between certain blades or vanes 40 14 and are connected at their inner ends to the disk 18 and at their outer ends to the stays 21. These rods 41 are connected at suitable intervals by couplings 42 and between the outer pair of couplings the rods 45 are slightly curved and support slightly

curved strips 43 between which the governor arms 22 project and are guided in their movement by said curved strips preventing lateral displacement, or, in other words, supporting the arms against the tendency to 70 bend laterally. The strips 43 are made with perforated lugs 44 at their ends receiving the rods 41 and are held against longitudinal movement by the couplings 42. The outer ends of the governor arms 22 are connected by links 45 with the blades or vanes, and said blades or vanes are made with eyes or loops 46 for the attachment of the links above described. These links 45 have outwardly projecting hooked ends 49 which 75 facilitate the assembling of parts and form a firm connection between the governor arms and the blades or vanes.

In Fig. 3 I illustrate a longitudinal section and in Figs. 4, 5 and 6 I illustrate 80 cross-sectional views of the blades or vanes, from which it will be noted that the outer ends of the blades or vanes are provided with stiffening ribs 50 and plates 51 to strengthen the spoke bearing 48.

In Fig. 9, I illustrate the preferred way of connecting the guys 17 with the stays 21, in which it will be noted that the ends of the guys are bolted together, forming a secure connection and leaving but a single 95 eye 21' for attachment to the spoke 13 which serves the purpose of connecting both the guy and the stay.

As above indicated, this invention is designed as an improvement upon the structure illustrated in my prior Patent Number 626,559, and the operation of the parts in general is the same, the improvements of this application being specific to certain features and in the description above I have 100 laid emphasis upon such features only as appear to be novel.

The invention, of course, is not limited to the precise details of construction, but to improved features which coöperate in the 105 production of the windmill which is an improvement as a whole in the art.

One of the most essential features of my invention is the automatic control which prevents the wind wheel from being thrown 110 entirely out of operation by a sudden gust of wind. This mechanism is illustrated best in Figs. 1, 7 and 8, Fig. 7 showing the normal position of parts. As above explained, when a sudden gust of wind operates the 115 governor, the arm 35 will engage the frame A and prevent further movement of the blades or vanes, thus holding them at a slight incline to compel the wind wheel to turn, and after the sudden gust of wind has 120 passed, the parts will return to their former positions and operate as before. By adjusting the length of the arm 35, through the medium of the bolt 41 at the free end thereof, the exact movement caused by a gust of 125 130

wind can be regulated and the mill can be thrown entirely out of operation at any time desired by a pull on the rod 40, as above explained.

5 Various slight changes may be made in the general form and arrangement of parts described without departing from the invention, and hence I do not limit myself to the 10 precise details set forth, but consider myself at liberty to make such changes and alterations as fairly fall within the spirit and scope of the appended claims.

I claim:

1. A windmill, having spokes, vanes 15 mounted to turn on the spokes, connections between the vanes to turn them all together, links connecting the spokes, governor arms pivoted upon and turning with the mill, means limiting the angular or pivotal movement 20 of the blades or vanes caused by a sudden gust of wind, and a rod connected to said means and adapted to be operated to throw the mill out of operation.

2. The combination with a windmill, of 25 governor arms controlling the angular disposition of the vanes of the windmill, a link movable longitudinally by said governor arms, a bell crank lever connected at one 30 end to said link, and an arm on said bell crank lever adapted to engage the windmill frame to limit the operating movement of the governor.

3. The combination with a windmill, of 35 governor arms controlling the angular disposition of the vanes of the windmill, a link movable longitudinally by said governor arms, a bell crank lever connected at one 40 end to said link, an arm on said bell crank lever adapted to engage the windmill frame to limit the operating movement of the governor, said arm having pivotal connection with the bell crank lever, and a 45 spring connecting the arm and lever and holding the same in normal position.

4. The combination with a windmill, of 50 governor arms controlling the angular disposition of the vanes of the windmill, a link movable longitudinally by said governor arms, a bell crank lever connected at one end to said link, an arm on said bell crank

lever adapted to engage the windmill frame to limit the operating movement of the governor, said arm having pivotal connection with the bell crank lever, a spring connecting the arm and lever and holding the same 55 in normal position, a lug projecting from said arm, and a rod connected to said lug and adapted to swing the arm out of position to engage the frame and permit the bell crank lever to be operated to throw the 60 windmill entirely out of operation.

5. A windmill, comprising a frame, a wind wheel supported on the frame, a governor controlling the angular disposition of the vanes of the windmill, an arm on the 65 frame, a bell crank lever pivotally supported on the arm, a link connecting one member of the bell crank lever with said governor, a shoulder on the other member of the bell crank lever, an arm pivotally connected to 70 the bell crank lever adjacent the shoulder, a spring normally holding said arm against the shoulder, and an adjusting bolt on the free end of said arm normally positioned above the frame and adapted to engage the 75 frame when the governor is caused to move by a sudden gust of wind tending to throw the blades out of operation, thereby limiting such movement of the blades.

6. A windmill, comprising a hub, spokes 80 extending from the hubs, guys at opposite sides of the spokes connected to their outer ends, certain of said guys comprising parallel rods, strips fixed to the parallel rods, and governor arms projecting between said 85 strips and supported against lateral movement by contact with said strips.

7. A windmill, comprising a hub, spokes extending from the hubs, guys at opposite sides of the spokes connected to their outer 90 ends, certain of said guys comprising parallel rods, strips fixed to the parallel rods, governor arms projecting between said strips and supported against lateral movement by contact with said strips, said strips 95 having perforated lugs at their ends receiving the rods, and couplings connecting the rods and limiting the longitudinal movement of the strips.

ORED OLSSON.
